FIG. 5

FIG. 6

INVENTOR:
CHARLES E. DAVIS
BY: Clarence J. Poole
ATTORNEY

UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

APPARATUS FOR HANDLING ORE AND THE LIKE.

Application filed October 10, 1921, Serial No. 506,713. Renewed June 5, 1924.

To all whom it may concern:

Be it known that I, CHARLES E. DAVIS, a citizen of the United States, residing at Chicago, in the county of Cook and State 5 of Illinois, have invented an Improvement in Apparatus for Handling Ore and the like, of which the following is a specification.

This invention relates to improvements in apparatus for handling ore and the like and 10 has for its principal object to provide an improved apparatus for transporting loose material from one place to another as for instance in a mine.

In two prior applications for U. S. Letters Patent, bearing Serial No. 382,696, filed 15 May 20, 1920, now Patent 1,462,688, July 24, 1923, and Serial No. 460,865, filed April 13, 1921, now Patent 1,464,522, Aug. 14, 1923, I have disclosed devices of the class 20 above described comprising a scraper and a movable frame adapted to form a support about which said scraper is guided. In the present application, I utilize the same general principles of construction and operation 25 as described in the above-mentioned applications, but provide a power element mounted on the frame adapted to engage the scraper and assist it in its forward movement about the frame during its digging 30 operation. I also provide means whereby the power element may be utilized to advance the frame toward the material to be transported at the will of the operator. My invention may best be understood by reference 35 to the accompanying drawings in which Figure 1 is a top plan view of the guiding frame constructed in accordance with my invention.

Fig. 2 is a side view of the frame shown 40 in Fig. 1.

Figs. 3 and 4 are detail views showing the ratchet mechanism for advancing the frame with respect to the material to be transported.

Fig. 5 is a top plan view showing the apparatus including the frame and scraper in operative position in a mine.

Fig. 6 is a side view of the apparatus shown in Fig. 5.

50 In the embodiment of my invention illustrated, the apparatus is adapted for use in mining operations in which loose material is to be transported from the working face or place from which the material is being

mined, to a place where it may be loaded on mine cars, and comprises a scraper 1 adapted to be moved on the mine bottom by means of flexible draft cables 2 and 3, and about a guiding frame 4 fixed on the mine bottom in position to form a bearing for one side of the scraper as the latter is advanced into the loose material. The frame 4 is held in place by means of a guiding device such as a pair of mine jacks 5 and 5^a of the usual type which are inserted in a longitudinally disposed slot 6 formed in the frame. The jacks 5 and 5^a are spaced apart so as to guide the movement of the frame in a longitudinal direction.

The specific form of frame 4 illustrated 70 herewith forms the subject matter of a pending application for U. S. Letters Patent Serial No. 506,712, filed Oct. 10, 1921, and comprises an arcuate shield or bearing member 12, a pair of longitudinally disposed 75 beams 13, 13, a rear end member 14, and suitable side frame members 15 and 16 connecting the shield 12 with the rear end member 14. The longitudinally disposed beams 13, 13, form the slot 6 in which the guide 80 members 5 and 5^a are retained. The forward or bearing face of the shield 12 is curved in a horizontal plane as shown in the drawings, and is provided with a centrally disposed recess or groove 17 extending 85 around the face thereof, a substantially vertical bearing surface 18 above said recess, and an outwardly and downwardly extending bearing surface 19 below said recess. The arrangement of the recess 17 and bearing surfaces 18 and 19 are clearly shown in cross-section in Fig. 2. A plurality of 90 sheaves 20, 20, are mounted about the shield and having their peripheries extending into the recess 17. The arrangement is such that 95 the draft ropes 2 and 3 are adapted to engage within the recess 17 and bear on the sheaves 20, 20. In case the draft ropes are allowed to slacken and fall to the ground, they will automatically be moved upwardly 100 along the inclined face 19 and into the recess 17, as soon as tension is applied to the ropes during the operation of the apparatus.

The scraper 1 is preferably of the bottomless type. The specific construction of 105 scraper illustrated herewith forms the subject-matter of a separate application filed by me Oct. 10, 1921, Serial No. 506,711, now

Patent 1,477,814, Dec. 18, 1923. Other suitable forms of scraper may be substituted if desired.

Referring now to the means for assisting the scraper as it is moved about the guiding frame 4, I provide a motor 40, such as an electric motor, mounted on a bracket 41 above the rear end piece 14 of the frame. Said motor is provided with a beveled ar-
5 mature pinion 42 meshed with a beveled gear 43 carried on a vertically disposed shaft 44. Said shaft 44 is mounted on suitable supports 45 and 46, connected to the frame member 14. A chain sprocket 47 is
10 carried on the bottom end of the shaft 44 and an endless chain 48 is trained about said sprocket and extends forwardly around the curved shield 12 at the front end of the frame. In the embodiment illustrated, the
15 endless chain 48 passes about the upper portion of the recess or groove 17 formed in the shield 12 and engages a plurality of anti-friction rollers 49, 49, adjacent the sheaves 20, 20, as clearly shown in Fig. 2. A
20 hook member 50 is mounted on and carried by the chain and is arranged so as to extend outwardly beyond the lateral face of the frame in position to engage the scraper 1 and assist it in moving about the front end
25 of the frame. The scraper 1 is provided with a suitable detent, such as an aperture 51 formed adjacent the forward edge of the inner wall 1^a to be engaged by the hook 50 as shown in Fig. 5.

30 By means of the mechanism just described, the hook 50, carried by the power actuated chain 48 may be controlled by the operator so as to engage the reciprocable scraper when it reaches its digging position, facing the forward end of the frame as shown in dotted lines in Fig. 5. With a device of the type shown and described, I find that much more power is required to move the scraper about the forward end
35 of the frame to gather the load, than is required to transport the scraper after the load has been gathered. My improved apparatus, therefore, produces an economically operated device in which the scraper is assisted by auxiliary power means during its loading movement.

The power from the motor 40 is also utilized for advancing the frame 4 toward the material to be transported. This means
40 comprises a gear 55 loosely mounted on the shaft 44 and meshed with a gear 56 mounted on the upper end of a shaft 10 and operatively connected to a winding drum 11. A draft rope 11^a is wound around the drum 11 with one end thereof connected to one of the forward jacks, such as the forward jack 5, as shown in Fig. 6. A ratchet wheel 9 is carried on the shaft 10 and is engaged by a dog 9^a adapted to prevent rotation of the
45 ratchet wheel and winding drum connected

therewith in one direction. Said dog may be maintained in operative connection with the ratchet wheel 9 by any suitable means such as a pivoted latch 9^b (see Figs. 3 and 4). Said latch 9^b has a pair of downwardly extending arms adapted to engage a lug 9^c carried by the dog 9^a to hold said dog in place by gravity. When it is desired to release the winding drum, the latch 9^b is rocked on its axis as shown in dotted lines in Fig. 4, to withdraw the dog 9^a from ratchet wheel 9. A clutch member 58 is interposed between the driving shaft 44 and the pinion 55 so that the winding drum may be operated at will when it is desired to advance the frame.

Although I have shown and described one form in which my invention may be embodied, it will be understood that many other means may be employed for accomplishing the same results without departing from the spirit and scope of my invention. I do not therefore wish to be understood as limiting myself to the specific construction illustrated herein excepting as specifically limited in the appended claims.

I claim as my invention:

1. In an apparatus of the class described, a frame adapted to be fixed against lateral movement, a draft-operated conveyor device including a scraper adapted to have lateral engagement with said frame while said scraper is being loaded, an auxiliary power element mounted on said frame, and means affording operative engagement between said power element and said scraper while the latter is in engagement with said frame.

2. In an apparatus of the class described, a frame having a curved forward portion, a support for said frame adapted to be fixed against lateral movement, a draft-operated scraper having lateral engagement with said curved forward portion of the frame, and means for moving said frame forwardly with respect to its support, comprising an auxiliary, power element mounted on the frame, ratchet mechanism having operative connection with said support, and clutch means interposed between said power element and said ratchet mechanism.

3. In an apparatus of the class described, a frame adapted to be fixed against lateral movement, and having a curved bearing portion, a reciprocably-operated scraper, an endless flexible driving element trained about said curved bearing portion, means for detachably connecting said driving element and said scraper, and a power element mounted on said frame and operatively connected with said driving element.

4. In an apparatus of the class described, a frame adapted to be fixed against lateral movement, and provided with a curved forward portion having a horizontally-disposed groove therein, an endless flexible

- driving element trained about said groove, a reciprocably-operated scraper, means for detachably connecting said driving element with said scraper, and a power element 5 mounted on said frame and operatively connected with said driving element.
5. In an apparatus of the class described, a frame adapted to be fixed against lateral movement, and provided with a curved forward portion having a horizontally-disposed groove therein, an endless flexible driving element trained about said groove,
- a plurality of anti-friction rollers arranged about said groove and forming a support for said driving element, a reciprocably-operated scraper, means for detachably connecting said driving element with said scraper, and a power element mounted on said frame and operatively connected with said driving element. 15
- Signed at Chicago, in the county of Cook and State of Illinois, this eighth day of October, 1921. 20

CHARLES E. DAVIS.
